Primary Examiner—A. Hugo Word*Assistant Examiner*—Eric Watterson*Attorney, Agent, or Firm*—Bell, Seltzer, Park & Gibson[57] **CLAIM**

The ornamental design for a combined toilet seat cover, as shown and described.

DESCRIPTION

FIG. 1 is a side perspective view of a combined toilet seat and cover incorporating this new design;

FIG. 2 is a front elevation view;

FIG. 3 is a rear elevation view;

FIG. 4 is a top elevation view;

FIG. 5 is a bottom elevation view; and,

FIG. 6 is a side elevation view the opposite side being a mirror image thereof.

The broken lines shown in FIGS. 2, 3 and 6 are for illustrative purposes only and form no part of the claimed design.

FIG. 5.

FIG. 6.
